(57) **CLAIM**

The ornamental design for a radiation shield garment, as shown and described.

DESCRIPTION

FIG. 1 is a front perspective view of a radiation shield garment showing our new design in a deployed configuration;

FIG. 2 is rear perspective view thereof;

FIG. 3 is a front elevation view thereof;

FIG. 4 is a rear elevation view thereof;

FIG. 5 is a left side elevation view thereof;

FIG. 6 is a right side elevation view thereof; and

FIG. 7 is a top plan view thereof;

FIG. 8 is a rear perspective view of the radiation shield garment in a partially deployed configuration;

FIG. 9 is a rear perspective view of the radiation shield garment in an un-deployed configuration; and,

FIG. 10 is front perspective view of the radiation shield garment in a partially deployed configuration.

The broken-line features in the figures are for illustration purposes only and form no part of the claimed design.

1 Claim, 7 Drawing Sheets
